UNITED STATES PATENT OFFICE.

ISIDORE M. GOLDSTEIN, OF BROOKLYN, NEW YORK, ASSIGNOR TO NATHAN NESTLER, OF NEW YORK, N. Y.

SKIPPING ROPE.

Application filed January 14, 1927. Serial No. 161,047.

This invention relates to an improved skipping rope used for exercising purposes, and more particularly to the mode of connecting the ends of the rope to the handle 5 pieces.

One object of the invention is to provide a skipping rope with freely movable handles so that during the use of the device very little effort will be required to rotate the 10 same.

A further object is to provide a device of the above nature which will be simple, cheap to manufacture, and very efficient and durable in use.

15 The novel features characteristic of my invention are set forth with particularity in the appended claims. The invention itself, however, both as to its construction and mode of operation together with the objects 20 and advantages thereof, will best be understood by reference to the following description taken in connection with the accompanying drawing in which

Figure 1 is a cross-sectional view of one 25 of the handles, showing the mode of attachment of one end of the rope in accordance with my invention.

Figure 2 is a view similar to Figure 1 but showing the metal collar in front elevation.

30 Figure 3 is a cross-sectional view of the collar taken on the line 3—3 of Figure 2, showing the rope gripping prongs.

Figure 4 is a modification of the invention shown in Figures 1, 2 and 3.

35 Figure 5 is still another modification, and Figure 6 is a cross-sectional view taken on the line 6—6 of Figure 5.

According to the present invention, handle 1 is provided with a hollow 2 in its base 3, 40 and secured within said hollow and at the edge of the base is a washer 4. This washer 4 may be made of wood or any other suitable material and is glued to the base within the hollow or otherwise securely fastened 45 thereto. The washer is provided with a central circular hole 5 which receives one end of a rope 6 as shown in Figures 1 and 2.

It is very desirable that the rope have 50 freedom of movement within the base of the handle in all directions, and furthermore the connection should be substantially permanent and durable. To prevent wear and to reduce the frictional contact between the rope and the washer to a minimum, a metal 55 sleeve or collar 7 is snugly fitted over and

clamped down upon the end of the rope. The upper edge of sleeve 7 is shaped or turned back upon itself to substantially form a ring 8 of greater diameter than the sleeve itself. When the entire device is assembled 60 the turned back portion or ring 8 bears upon the edge of the central circular hole 5 of the washer. This construction is desirable in that the friction between sleeve 7 and inner surface of hole 5, and that between portion 8 65 and washer 4 becomes practically negligible as compared with known old devices.

The sleeve 7 is provided with two inwardly projecting lugs 9 for securely gripping the rope. These lugs 9 may be provided 70 with gripping prongs 10, although these are not essential.

In Figure 4 is shown a modified construction, wherein sleeve 11 is similar to 7 75 explained above except that the upper edge is not shaped or turned back upon itself, but remains straight. In addition a wire ring 12 is clamped around rope 6 just above or in abutting relation to the upper edge of sleeve 11. The outer diameter of this ring 80 should overlap the outer diameter of the sleeve to provide a sufficient bearing surface for the ring on the washer 4.

A still further modification is disclosed in Figure 5, where the metal for forming the collar or sleeve 13 is made of heavy gauge. In this case one edge is turned outwardly 85 to form a ledge or abutting surface 14. The body of the sleeve is punched out to form inwardly projecting prongs 15 for gripping 90 the rope. Of course, it is understood that prongs, such as 15, may be provided in the sleeves or collars shown in Figures 2 and 4.

And it is further understood that both 95 ends of the rope are provided with similar mechanism as fully explained above.

Having thus particularly described my invention, what I claim as new and desire to secure by Letters Patent, is:—

1. In a handle attachment for skipping ropes, in combination, a handle having a hollow portion, a rope-end arranged to be received within said hollow portion, a ring of circular cross-section clamped to the rope-end, and means provided with a central opening for allowing the rope-end to be disposed therethrough but retaining the ring within the hollow, said means being secured to the handle and substantially closing the hollow portion, thereby effectively retaining 100 105 110

the rope-end within the hollow, both the ring and the last-mentioned means forming in effect a swivelled joint.

2. In a handle attachment for skipping ropes, in combination, a handle having a hollow portion, a rope-end arranged to be received within said hollow portion, a ring of circular cross-section clamped to the rope-end, means provided with a central opening for allowing the rope-end to be disposed therethrough but retaining the ring within the hollow, said means being secured to the handle and substantially closing the hollow portion, thereby effectively retaining the rope-end within the hollow, both the ring and the last-mentioned means forming in effect a swivelled joint, and rope-protecting means, clamped to the rope-end adjacent the ring, passing through said central opening to provide for free movement of said rope-end within the handle, and also to prevent wear of same.

3. In a handle attachment for skipping ropes, in combination, a handle having a hollow portion, a washer secured to the handle substantially closing the hollow portion, said washer being provided with a central opening, a rope-end arranged to be received within said hollow portion and extending through the central opening of the washer, and means including a ring of circular cross-section and a sleeve clamped to said rope-end, the former rotatably retaining the rope-end within the handle and the latter preventing wear thereof against the washer.

4. In a handle attachment for skipping

ropes, the combination with a handle having a housing therein, of a rope-end, a sleeve clamped thereto, and a washer forming a wall of the housing having a central opening for allowing the rope-end to pass therethrough, and a ring of circular cross-section rigidly associated with said sleeve disposed within the housing of the handle and bearing against the edge of the central opening.

5. Means for providing a swivelled connection between a handle and a rope-end, said handle having a hollow portion, including a wearing plate snugly clamped throughout its length over the rope-end, a washer secured to the handle substantially closing the hollow portion, said washer having a central opening for receiving the rope-end to which the wearing plate is attached, and a ring of circular cross-section overlapping the edge of the central opening rigidly associated with the wearing plate for swivelly retaining the rope-end within the handle.

6. A handle attachment for skipping ropes comprising a handle provided with a hollow portion, a retaining member, having a central opening, wholly within said hollow portion, a rope-end extending through said central opening, a sleeve attached to said rope-end, said sleeve having a portion of greater diameter than said opening, retained within the hollow, and coacting with said retaining member.

Signed at New York, in the county of New York and State of New York, this 12th day of January, A. D. 1927.

ISIDORE M. GOLDSTEIN.
